INVENTOR
CHARLES F. WEEKS

BY

Harry Schneider
ATTORNEY

UNITED STATES PATENT OFFICE.

CHARLES F. WEEKS, OF ALAMEDA, CALIFORNIA.

TYPE-BAR-CASTING MACHINE.

Application filed February 7, 1923. Serial No. 617,468.

To all whom it may concern:

Be it known that I, CHARLES F. WEEKS, a citizen of the United States, residing at Alameda, in the county of Alameda and 5 State of California, have invented certain new and useful Improvements in Type-Bar-Casting Machines, of which the following is a specification.

My invention is an improvement in linotype machines.

In casting large letters, that is, forty-eight point, on a linotype machine it has been necessary to install a very elaborate and expensive mechanism, and also change 15 the mold on the machine.

With my invention the same mold and general mechanism is employed, the only change in the machine being that a portion of the vise is removably attached and upon 20 its removal the wider slug with the large letters can pass between the knife block and the vise.

In the drawing in which my invention is illustrated, I have shown it as applied to 25 the Mergenthaler linotype machine, but it may be applied to any machine employing the same principles. The drawing also illustrates a single column or twelve em slug, but my invention can be applied to any desired size such as double column and thirty 30 em.

In the annexed specification and appended claims, I desire to cover my invention in whatever form it may be embodied.

35 Referring to the drawings:

Figure 1 is a perspective view of a portion of the vise and mold with my invention attached thereto, and with the knife block removed for purposes of illustration.

40 Figure 2 is a rear perspective view of a portion of the vise, illustrating my invention attached thereto.

Figure 3 is a sectional view taken on the line 3—3 of Figure 2.

45 Referring more particularly to the drawings, the numeral 1 indicates a linotype vise of a well known construction, which is formed with a slide 2 extending to an assembling rack 3. A trimming blade 1^a is formed on said vise, the purpose of which will be described later. The mold 4 is driven by the gear 5 in the usual manner. A knife block A is secured to the vise 1 and spaced therefrom in the usual manner. The slug 6 is shown in Figure 1 in the process of ejec-

tion from the mold. This slug has large letters cast upon it and it will be seen that the standard machine would trim the letters, to the width of the slug, between the blade 1^a and the knife block as the slug 60 was ejected between them. To allow for this additional width, I cut a channel 7 in the blade 1^a of any desired height, that is, single or double column, etc., and of a sufficient depth that the large letters will just 65 clear the channel. When it is desired to use the machine for standard work a slide 8 provided with a trimming edge is provided to fill the channel 7. A guide 9 is formed on the slide 8 which is adapted to 70 set at one edge of the slide 2 and prevent the slugs from falling off. A handle 10 is provided on the slide 8 to facilitate its easy removal. A plate 11 is secured to the slide and it is formed with a lug 12 which 75 rests against the vise 1. A holding screw 13 is screwed into the vise 1 and extends through the lug 12 and has formed upon it two pins 14 which engage said lug to hold the slide securely in place.

Having described my invention, I claim:

1. In combination with a type bar casting machine having a vise, a trimming blade on said vise, a portion of said blade being removed and a knife block adjacent said trimming blade, and means on said blade for permitting the space between said blade and said knife block to be increased by removal.

2. In combination with a type bar casting machine having a vise, a trimming blade on said vise and a knife block adjacent said trimming blade, said blade having a channel formed therein, and removable means for filling said channel.

3. In combination with a type bar casting machine having a vise, a trimming blade on said vise and a knife block adjacent said trimming blade, said blade having a channel formed therein, a removable slide forming a part of said blade and adapted to fit into said channel, and means for holding said slide in said channel.

4. In combination with a type bar casting machine having a vise, a trimming blade on said vise and a knife block adjacent said trimming blade, said blade having a channel formed therein, a removable slide forming a part of said blade and adapted to fit into said channel, a plate secured to said 110

slide, said plate having a lug formed thereon which is adapted to rest against said vise, and a screw carrying pins extending through a slot in said lug into said vise.

5. In combination with a type bar casting machine having a vise, a trimming blade on said vise, a knife block adjacent said

trimming blade, said blade having a channel formed therein, removable means for filling said channel, and a type guide carried ¹⁰ by said removable means.

In testimony whereof I affix my signature.

CHARLES F. WEEKS.
